US0D1021627S

(12) **United States Design Patent** (10) **Patent No.:** **US D1,021,627 S**
(45) **Date of Patent:** **** Apr. 9, 2024**

(54) **PACKAGING FOR ACCESSORY**

(71) Applicant: **Apple Inc.**, Cupertino, CA (US)

(72) Inventors: **Arsalan Aslam**, Santa Clara, CA (US);
Grace Tsai, San Francisco, CA (US);
David Samuel Kumka, San Francisco, CA (US); **Molly Anderson**, San Francisco, CA (US); **Clement Tissandier**, San Francisco, CA (US)

(73) Assignee: **Apple Inc.**, Cupertino, CA (US)

(**) Term: **15 Years**

(21) Appl. No.: **29/853,304**

(22) Filed: **Sep. 14, 2022**

(51) LOC (14) Cl. **09-07**

(52) U.S. Cl. **D9/456**
USPC ....

Goldstein & Fox P.L.L.C.

(57) **CLAIM**

The ornamental design for packaging for accessory, as shown and described.

DESCRIPTION

FIG. 1 is a front isometric view of packaging for accessory showing the claimed design;
FIG. 2 is a rear isometric view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof; and,
FIG. 8 is a bottom plan view thereof.

1 Claim, 6 Drawing Sheets
